LEWING L. MITCHELL, OF BROOKLYN, NEW YORK, ASSIGNOR TO DAVID ROBBINS, OF NEW YORK, N. Y.

VENDING MACHINE

Application filed July 8, 1931. Serial No. 549,557.

My present invention relates to vending machines, and more particularly to an improved vending machine of the coin-controlled type.

One of the main objects of my invention is to provide a novel, improved and fool-proof vending machine of the coin-controlled type for vending measured quantities of merchandise sold in bulk, and stored for the supply in a receptacle superposed on the measuring device, the merchandise being fed by gravity to the delivery mechanism, the improvement resulting in reliable action in vending, measuring, and delivery, and being even adapted for vending articles of irregular shape without danger of clogging or costly servicing.

The novel features which I believe to be characteristic of my invention are set forth in particularity in the appended claims, the invention itself, however, as to both its organization and method of operation will best be understood by reference to the following description taken in connection with the drawings in which I have indicated diagrammatically one construction whereby my invention may be carried into effect.

In the drawings,

Fig. 1 is a front elevation of such parts of the apparatus as are involved in the invention,

Fig. 2 is a plan view of the apparatus shown in Fig. 1,

Fig. 3 is another plan view of the apparatus shown in Fig. 1, certain of the elements shown in the latter being removed,

Fig. 4 is a side elevation of the wiper device embodied in the present invention,

Fig. 5 is a rear elevation of the same device,

Fig. 6 is a view of the underside of the device shown in Figs. 4 and 5.

Referring now to the accompanying drawings in which like characters of reference indicate the same parts in the different views there is shown in Fig. 1 a portion of an apparatus wherein a predetermined bulk of small articles may be withdrawn from a receptacle, after the insertion of a coin which alone will render the movable parts of the

apparatus operative for that purpose. Only so much of the apparatus is shown as is essential to a clear understanding of the present invention. Those skilled in the art are acquainted with this type of vending machine which comprises a case 1 of substantially square cross-section, the front of the case usually being left open to receive a glass closure, the flanges 2, 2 usually being provided on the front of the case to provide a guide for inserting such a glass closure.

The apparatus is of a very simple construction and includes a base plate 3 (the construction of which is shown in detail in Fig. 3) which divides the case into an upper portion 4 for receiving the articles to be vended, and a lower portion 5 which has disposed therein the delivery chute 6. The base plate 3 is of substantially the same configuration as the cross-section of the case, and is also provided with a cut-away portion 7 whereby the coin control mechanism (not shown) may be arranged adjacent the driving gear of the measuring wheel to be described hereinafter.

The plate 3 is provided with rear and side flanges 8, and these flanges may be secured to the walls of the case by any well known securing means, such as for example rivets 9. The upper edges of each of the flanges 8 are bent to form securing means 10, this being accomplished by bending the top edge of each flange forwardly, and bending a portion of the forwardly bent edge to the rear, each rearwardly bent portion being spaced from its adjacent case wall. Thus three such rearwardly bent flanges 11 are provided above the plate 3. It will be seen that the flanges 8 extend a considerable distance above the plane of the plate 3.

As a matter of fact it is preferable to have the height of the flanges 8 such as to make it substantially equal to the height of the measuring wheel 12 to be shortly described. The base plate 3 is, furthermore, provided with an outlet aperture 13, the latter preferably having a configuration as shown in Fig. 3. The delivery chute 6 has its upper flange 14 secured to the underface of the plate 3 by any means (not shown) well known to those skilled in the art. A side wall 15 of the chute

may also be secured to the adjacent wall of the casing 1 in any desired manner. It will of course be clearly understood that the lower opening of the chute 6 may terminate outside the lower portion of the case in any desired manner (not shown). It is again pointed out that the view in Fig. 1 shows a front elevation of a vending machine well known to those skilled in the art wherein the coin-control actuating mechanism and the entire front slidable wall of the case have been removed, the upper portion of the case 1 and the lower portion thereof being partly broken away in order to preserve simplicity of description.

15 The chute 6 for the articles delivered communicates at its upper end with the outlet opening, or aperture, 13, it being clearly understood that the lower end of the chute, is usually closed by a pivotable closure to be 20 opened only for removing the articles delivered through the chute 6. It will also be seen that the upper end of the chute 6 has a considerably greater area than that of the outlet 13, and overlaps the latter.

25 A horizontal turn-table or measuring wheel 12 is mounted upon the plate 3, the table being provided with a plurality of spaced radial slots 16, there being six such slots provided in the present case. The table commonly employed in this type of machine has a hollow interior, the hub 17 thereof having each of six spaced portions 18 functioning as an inner wall of each slot 16, it being understood that the interior of the hub 17 is hollow.

30 It will now be appreciated that each slot 16 comprises an inner wall 18, an opposite wall 19 and two centrally converging side walls 20, the top and bottom of each slot being open. As the table, or wheel 12, is rotated upon its axis, the under-peripheral rim of the wheel is in substantially sliding contact with the upper face of the plate 3 thereby permitting the latter to function as a bottom for each slot 16, except when a slot moves into registry with the outlet aperture 13 of the base plate 3. When such registration occurs, of course, any articles which may have been entrapped between the walls 18, 19, 20, and supported by the plate 3, are dropped into the delivery chute 6 by gravity, when a given slot 16 moves over the aperture 13. In this way, delivery of articles is simply and satisfactorily secured.

35 The configuration of each slot 16 is of substantially the same configuration as that of the outlet aperture 13, with the exception that the area of the latter is somewhat greater than that of any one slot 16. The upper peripheral rim of the wheel 12 is provided with a circle of spaced teeth 21, the latter functioning as the driven means whereby rotation of the wheel 12 upon its axis is secured. The teeth slightly overhang the outer rim 12' of the wheel. As is well known to those skilled in

the construction of this type of vending machine the teeth are so proportioned that movement of a manually operated, coin control, driving pinion through a predetermined arc results in a movement of the wheel 12 through an arc in the direction of the arrow shown in Fig. 2, which arc is sufficient to bring a loaded slot 16 in registration with the outlet aperture 13. The manual control pinion and its associated coin control mechanism are not shown for the reason that they are well known to those skilled in the art, and also since they do not form the subject matter of this invention, it being believed to be sufficient for the present purpose to point out that the teeth 21 are adapted to be driven by means of any well known type of coin controlled pinion to move the measuring turn-table through a predetermined arc every time a coin is placed in the coin-control mechanism.

As stated heretofore the height, or depth, of the table 12 is such that its upper face is in substantial alignment with the upper edges of the flanges 8 of the base plate 3. This arrangement is provided in order to permit the positioning of a hopper device, generally denoted by the reference numeral 22, above the upper face of the measuring turn-table. The hopper comprises a plate whose outer edges are substantially similar in extent and shape to that of the case walls, and is additionally provided with a central opening, the latter having a diameter such that the periphery 23' of the opening is substantially in alignment with the periphery 12' of the measuring wheel. As shown in Fig. 2 the periphery 23' of the hopper 22 is concentric with the circle which includes the walls 19 of each slot 16. From Fig. 1 it will be observed that the plane of the opening of said hopper is spaced from the plane including the outer edges 24 of the hopper.

It will be, furthermore, observed that the hopper is maintained in fixed position with respect to the base plate 3 by curving the side and rear edges 24 so that each such edge 24 may be disposed in hooked relation with each rearwardly bent edge 11 of each flange 8 of the base plate 3. It will now be seen that every portion of the hopper plate 22 slopes downwardly, and at an angle, towards the periphery 23' of the hopper opening. This is represented by the inclined outer periphery 25, in Fig. 1. The line 23' of the hopper opening is so positioned with respect to the upper face of the measuring wheel that sliding contact between the rim 23' and the upper face of the wheel 12 is permitted without binding between the two.

It will be appreciated that the hopper 22 also serves as a false bottom for the storing receptacle portion 4, and, due to the sloping face of the hopper, guides the articles stored in the portion 4 above the hopper towards the slot 16. It is quite obvious that some

device is necessary to insure the delivery of a slot full of articles, and no more.

Clearly, assuming the entire space 4 filled with articles, the lower articles of the storage space 4 resting upon the sloping face of the hopper 22 and completely filling all the slots 16, and covering as well the portions 20' between slots 16, as soon as a slot 16 moved into registration with the outlet aperture 13 there would be an endless flow of articles through the delivery chute. It will therefore be seen that it is essential in a device of this type to not only remove the surplus articles heaped in a slot 16 above the plane of the upper surface of the wheel 12, but it is essential to provide an arrangement which will simultaneously prevent articles from the space 4 from entering into a slot 16, which is in registration at that moment with the opening 13, as the said slot 16 is unloaded.

Still another factor must be considered in accomplishing these features. It often happens, particularly when irregular objects are being vended, that an object which protrudes above the plane of the upper face of the wheel 12 is wedged in such protruding position between the converging walls of a slot 16. In such a case, obviously, the combined wiper and guard device to be employed should be of such a construction that there is no opportunity for such protruding articles to jam or lock the measuring wheel against further rotation. Furthermore, such a construction should not only be simple and fool-proof, but should be self-adjustable to accommodate itself to irregular, or regular, objects of varying width, and varying degrees of protrusion beyond a slot 16. The device to be herein-after described in detail permits the accomplishment of these various functions in a highly simplified and novel construction.

The combined article guard and wiper is shown in detailed construction in Figs. 4, 5 and 6, and as shown therein consists of a hollow casing, or box, provided with four walls, two of the walls 30, 31 being rigid plates secured to each other at adjacent edges thereof, the other two walls of the wiper device each comprising a plurality of aligned, independently flexible spring coils. In Fig. 6, which shows a view of the wiper device from underneath thereof, it will be seen that the resilient wall 32, opposite the plate wall 31, comprises a row of six coil springs, and that the wall 33, opposite the wall plate 30, also consists of a row of six coils. As shown in Fig. 4 each of the coils 34 forming the wall 32 is secured at its upper end thereof, by soldering or otherwise, to the cover plate 35 from which the walls 30 and 31 depend.

In the same manner it will be observed, as shown in Fig. 5, that the coils 36, forming the resilient wall 33, are likewise secured at each upper end to the plate 35, six coils 36 being provided in this wall as well. It will

be seen that, in the case of the coils 34, the coil adjacent the wall 30 extends considerably beyond the lower edge of the said wall, and that each succeeding coil is slightly longer than the coil preceding it. It will also be observed that, as shown in Fig. 5, that the coil 36 adjacent the last of the coils 34 is of substantially the same length as the said coil 34, while each succeeding coil 36 is of less length than each preceding one. The last of the coils 36 is preferably of about the same length as the coil 34 adjacent the wall 30.

It will now be seen that the wiper device has an open bottom, and that each of the resilient walls 32 and 33 comprises a series of independently flexible spring members, specifically coils, and that moreover each of the walls 32 and 33 is self-adjustable to permit the movement of articles of varying width from a point outside the wall 33 into the interior of the casing, and out again through the wall 32, to a point outside the casing. Of course, the reverse movement is also true.

It will therefore be seen that one of the two walls, 32, 33 may function as a self-adjustable entrance into the interior of the casing, and the other wall as a self-adjustable exit out of the casing. In order to provide a means for securing the aforementioned combined guard and wiper device, a cap plate 40 is affixed, as by means of a rivet 41, to the outer face of the cover plate 35 of the casing, the cap plate being provided with short flanges 42, and two corner securing legs 43, 44. The leg 43 is provided at a corner between a coil 34 and a coil 36, and is of substantially the same length as both these coils. On the other hand, the leg 44 is provided at the corner adjacent the chute coil 36, and is of substantially the same length as the walls 30, 31.

Each of the legs 43, 44 is provided with an apertured securing toe 45, 45', the toe 45' being part of the leg 44. It will be noted from Figs. 4, 5 and 6 that the coils in each row of coils are slightly spaced from each other. However, this spacing should be just sufficient to permit ready flexure of any given coil without binding with any other coil.

In Figs. 1 and 2 I have shown the manner in which the combined wiper and guard device, shown in Figs. 4, 5 and 6, is mounted upon the sloping upper face of the hopper 22, and upon the upper face of the hub 17 of the measuring wheel 12. The toe 45' of the leg 44 is secured in any well known manner, as by a bolt, to a portion of the sloping upper face of the hopper 22 immediately adjacent the periphery 23' of the hopper opening. The toe 45 is similarly secured to the central portion of the upper face of the hub 17 of the measuring wheel, while the wall 30 is secured similarly to an upstanding flange 50, partly bent of the hopper 22.

It will be observed that the wall 30 extends

above the hopper, and that the combined guard and wiper casing completely covers a given slot 16 when it is in registration with the aperture 13. It will also be seen that the resilient walls 32 and 33 are so arranged with respect to the slot 16 of the measuring wheel, that the row of coils 36 have their lower edges in wiping contact with the upper face of the measuring wheel. This is also true of the row of coils 34. It will likewise be appreciated that the row of coils are arranged substantially at an angle equal to 90° to each other, and that each row of coils extends radially from substantially the center of the hub 17, to the periphery portion 23' of the hopper 23.

The reason for having the coils successively longer as they approach the leg 43, and having the coils 36 successively shorter as they approach the leg 44 will now be seen. Obviously, since the upper face of the hopper 22 surrounding the periphery 23' slopes upwardly, the coils towards the hub 17 should be somewhat longer than coils closer to the periphery of the hopper opening. In this way, there is assured a substantially constant wiping relation between all of the coils 36 and 34 with respect to the upper face of the measuring wheel.

The operation of the present invention is now believed to be clear with the aid of the above description and the drawings. As has been explained heretofore upon movement of the manually actuated coin-control, driving pinion, the measuring wheel is rotated through a predetermined arc. Assuming that the entire space surrounding the hopper 22 and the upper face of the measuring wheel 12 are full of articles of varying shapes and widths to be vended, and assuming that the measuring wheel is moving in a direction of the arrow shown in Fig. 2, it will be seen that as the slot 16' in Fig. 2 approaches the row of coils 36, the first action of the coils is to level off the articles in slot 16' so that only a substantially exact slot-full of articles will enter into the interior of the guard casing.

Now, if there are no articles held in the slot 16' which protrude beyond the plane of the upper face of the measuring wheel 12, no one of the coils will be flexed, merely wiping action only being accomplished in such a case.

However, if any article in slot 16' protrudes beyond the plane of the upper face of the measuring wheel, such an article will bend as many coils as are in the path of the article. If the article is as wide as two coils, then two coils will be bent towards the interior of the casing, and in that way there never can be any jamming or binding between wiping device and the measuring wheel. It will now be seen that due to the independent flexibility of the coils 36, the

wiping wall 33 is self-adjustable to permit articles of varying width, protruding from the slot 16', to pass by the wall. It should be understood that it is much more desirable to have an article protruding beyond the upper opening of the slot 16', and thus deliver perhaps slightly more than the coin's worth, than to have a jamming action occur between the wiping device and the measuring wheel.

When the slot 16' has moved into the interior of the casing and in registration with the aperture 13, the contents of the slot 16' of course, is emptied by gravity into the chute 6. If the protruding article has been jammed between the converging walls 20 of the slot 16' upon a further actuation of the measuring wheel in the direction of the arrow (that is, when another coin is employed to move the wheel) it is again essential to guard against jamming between the guard casing and the measuring wheel. If the wall 32 were rigid, as the walls 30 and 31, then it is easily seen that when the slot 16' moved towards the outside of the casing that the protruding article would pass safely through the wall 33 to be jammed between the wall 32 and the measuring wheel. However, by having the coils 34 independently flexible, the same action will take place as was explained in connection with the coils 36.

In other words, such coils 34 which are in the path of the protruding article will be pushed outwardly and thus permit the article wedged in the slot 16' to safely move out of the casing interior. It will thus be seen that the wall 32 serves as a self-adjustable exit wall and guards against jamming or binding at that point.

Other advantages of this combined novel and fool-proof wiper and guard device will readily occur to those skilled in the art. It is to be clearly understood that the present explanation of the operation of this device does not include all the possible evils guarded against by the present invention, but that jamming, binding or other disadvantages requiring costly servicing are eliminated by the use of the present invention.

Moreover, while I have indicated and described one arrangement for carrying my invention into effect, it will be apparent to one skilled in the art that my invention is by no means limited to the particular organizations shown and described, but that many modifications may be made without departing from the scope of my invention as set forth in the appended claims.

What I claim is:

1. In a vending machine, the combination with a base plate, of a frame provided with a circular opening spaced from said plate, a horizontally mounted turn-table mounted on said plate and provided with a plurality of spaced, radial compartments, an outlet aperture in plate below said table adapted to

register with said compartments, a receptacle surrounding said frame, and a wiper device, secured to said frame, extending over a portion of said table and including a pair of 5 angularly disposed rows of resilient coils.

2. In a vending machine, the combination with a base plate, of a frame provided with a circular opening spaced from said plate, a horizontally mounted turn-table mounted on 10 said plate and provided with a plurality of spaced, radial compartments, an outlet aperture in plate below said table adapted to register with said compartments, a receptacle surrounding said frame, and a wiper device, secured to said frame, extending over a portion of said table and including a pair of 15 angularly disposed rows of resilient coils, said coils being relatively movable.

3. In a vending machine, the combination with a base plate, of a frame provided with a circular opening spaced from said plate, a horizontally mounted turn-table mounted on said plate and provided with a plurality of spaced, radial compartments, an outlet aperture in plate below said table adapted to register with said compartments, a receptacle surrounding said frame, and a wiper device, secured to said frame, extending over a portion of said table and including a pair of 25 30 angularly disposed rows of resilient members, said device being arranged in substantial alignment with said outlet aperture.

4. In a vending machine, a receptacle for the goods to be vended, a base plate for said receptacle provided with an outlet aperture, a delivery chute disposed under said plate and aligned with said aperture, a horizontal measuring wheel rotatably secured to said plate, said wheel being provided with a plurality of spaced, radial slots, each of said slots being of substantially the configuration of said aperture, a false bottom spaced from, and secured to, said plate and provided with an opening, the periphery of the latter contacting with the periphery of the upper face of said wheel, a hollow guard casing secured to said bottom, said casing being arranged to overlap a portion of said wheel upper face, two walls of said casing comprising a plurality of substantially vertical, independently flexible members, all of said members being in wiping relation to said wheel upper surface, the members in each of 45 50 said walls consisting of coils in alignment.

5. In a vending machine, a receptacle for the goods to be vended, a base plate for said receptacle provided with an outlet aperture, a delivery chute disposed under said plate and aligned with said aperture, a horizontal 60 measuring wheel rotatably secured to said plate, said wheel being provided with a plurality of spaced, radial slots, each of said slots being of substantially the configuration of said aperture, a false bottom spaced 65 from, and secured to, said plate and provided

with an opening, the periphery of the latter contacting with the periphery of the upper face of said wheel, a hollow guard casing secured to said bottom, said casing being arranged to overlap a portion of said wheel 70 upper face, two walls of said casing comprising a plurality of substantially vertical, independently flexible members, all of said members being in wiping relation to said wheel upper surface, said casing being arranged in substantial alignment with at least one of said slots and said base plate aperture.

6. In a vending machine, a receptacle for the goods to be vended, a base plate for said 80 receptacle provided with an outlet aperture, a delivery chute disposed under said plate and aligned with said aperture, a horizontal measuring wheel rotatably secured to said plate, said wheel being provided with a plurality of spaced, radial slots, each of said 85 slots being of substantially the configuration of said aperture, a false bottom spaced from, and secured to, said plate and provided with an opening, the periphery of the latter contacting with the periphery of the upper face of said wheel, a hollow guard casing secured to said bottom, said casing being arranged to overlap a portion of said wheel 90 upper face, two walls of said casing comprising a plurality of substantially vertical, independently flexible members, all of said members being in wiping relation to said wheel upper surface, the members in each of 95 said walls consisting of coils in alignment.

7. A wiper device for a vending machine measuring wheel comprising a hollow casing, each of at least two walls thereof comprising a plurality of aligned, independently flexible, resilient coils adapted to be disposed in wiping relation to said wheel surface.

IRVING L. MITCHELL.
